[57] CLAIM

The ornamental design for a rear view mirror, as shown and described.

DESCRIPTION

FIG. 1 is a perspective view of the front, top and one side of a rear view mirror showing my new design which is mountable on the left side of an automobile; FIG. 2 is a front elevational view thereof; FIG. 3 is a perspective view of the front, bottom and other side thereof;

FIG. 4 is a bottom plan view thereof;

FIG. 5 is a rear elevational view thereof;

FIG. 6 is an elevational view of said one side thereof;

FIG. 7 is an elevational view of said other side thereof;

FIG. 8 is a top plan view thereof;

FIG. 9 is a perspective view of the front, top and one side of a rear view mirror showing a second embodiment of my new design, the sole difference being that it is mountable on the right side of an automobile;

FIG. 10 is a front elevational view of the embodiment of FIG. 9;

FIG. 11 is a perspective view of the front, bottom and other side of the embodiment of FIG. 9;

FIG. 12 is a bottom plan view of the embodiment of FIG. 9;

FIG. 13 is a rear elevational view of the embodiment of FIG. 9;

FIG. 14 is an elevational view of said one side of the embodiment of FIG. 9;

FIG. 15 is an elevational view of said other side of the embodiment of FIG. 9; and

FIG. 16 is a top plan view of the embodiment of FIG. 9.
